United States Patent

Des. 239,990
Patented May 25, 1976

239,990

ARM CHAIR

Henry Olko, Applegreen Drive,
Old Westbury, N.Y. 11568

Filed Aug. 20, 1974, Ser. No. 499,018

Term of patent 14 years

Int. Cl. D6—01

U.S. Cl. D6—57

Fig. 4

FIG. 1 is a side view of an arm chair embodying my design;

FIG. 2 is a rear view of the arm chair of FIG. 1;

FIG. 3 is a front view of the arm chair of FIGS. 1 and 2; and

FIG. 4 is a perspective view of the arm chair of FIGS. 1, 2 and 3.

I claim:

The ornamental design for the arm chair, as shown.
